US00D699514S

(12) **United States Design Patent**
Lovley, II et al.

(10) **Patent No.:** **US D699,514 S**
(45) **Date of Patent:** **** Feb. 18, 2014**

(54) **MULTI-FUNCTIONAL FOOD PREPARATION PLATFORM**

(71) Applicant: **Bravo Sports**, Santa Fe Springs, CA (US)

(72) Inventors: **Jack B. Lovley, II**, Lake Forest, CA (US); **Marvin S. Dobert**, Bolton Landing, NY (US); **Mark Groenhuyzen**, Huntington Beach, CA (US); **Joseph C. Klingl**, Los Angeles, CA (US); **Jerry Sharber**, Cypress, CA (US)

(73) Assignee: **Bravo Sports**, Santa Fe Springs, CA (US)

(**) Term: **14 Years**

(21) Appl. No.: **29/458,065**

(22) Filed: **Jun. 14, 2013**

Related U.S. Application Data

(63) Continuation of application No. 29/400,750, filed on Aug. 31, 2011, now Pat. No. Des. 684,423.

(57) **CLAIM**

The ornamental design for a multi-functional food preparation platform, as shown and described.

DESCRIPTION

FIG. 1 is a perspective view of a multi-functional food preparation platform.

FIG. 2 is a top plan view of the multi-functional food preparation platform of FIG. 1.

FIG. 3 is a bottom plan view of the multi-functional food preparation platform of FIG. 1.

FIG. 4 is a side elevational view of the multi-functional food preparation platform of FIG. 1.

FIG. 5 is another side elevational view of the multi-functional food preparation platform of FIG. 1.

FIG. 6 is another side elevational view of the multi-functional food preparation platform of FIG. 1; and,

FIG. 7 is another side elevational view of the multi-functional food preparation platform of FIG. 1.

The broken lines in the drawings are for illustrative purposes only and form no part of the claimed design.

1 Claim, 4 Drawing Sheets
